UNITED STATES PATENT OFFICE

ARTHUR MÖHRLE, OF STUTTGART, GERMANY, ASSIGNOR TO ROBERT BOSCH AKTIEN
GESELLSCHAFT, OF STUTTGART, GERMANY

STARTING CARTRIDGE

Application filed April 24, 1929, Serial No. 357,823, and in Germany October 2, 1928.

The invention relates to crude oil engines and to the ignition device, cartridge or insert element adapted to be inserted into the cylinder which automatically ignites at the compression temperatures set up in the cold cylinder in turning over the engine and then continues to burn until the engine is running.

The known devices of this type consist of ordinary gun cotton or gun cotton treated with camphor. The ignition temperatures of such devices however, are either so high that they only ignite with difficulty, particularly in small capacity cylinders or else ignition takes place so rapidly that the tinder or other carrier is not ignited by it.

Much improved conditions are obtained when the ignition of the device in accordance with the present invention, is facilitated by an easily ignited phosphorous compound which is applied to the device in any suitable manner.

The invention is more particularly described with reference to the accompanying drawing presenting a longitudinal sectional view of the device.

The insert element *a* in form of a cartridge consists of a match or paper impregnated with saltpetre. To that end of the cartridge which projects—when inserted—into the cylinder, is applied by adhesive means a phosphorous compound *b*, such as phosphorous sesqui-sulphide, the ignition temperature of which is in the neighbourhood of 100° C.

In order to protect the device against external influences before use, it is preferable to completely enclose at least the portion provided with the easily ignited phosphorus compound, by means of a paper jacket *c* which is preferably opened or torn before insertion of the device in the cylinder.

Instead of applying the phosphorus compound to the insert element *a* by adhesive means, the cartridge may be completely or partially saturated with a solution of a phosphorus compound.

It will be appreciated that in an internal combustion engine operated with the ignition device as described the charge in the cold cylinder need only be compressed to raise its

temperature to 100° C. whereupon the engine will subsequently run under self ignition.

Having now particularly described and ascertained the nature of my said invention and in what manner the same is to be performed, I declare that what I claim is:—

1. A cartridge adapted to be inserted in the combustion chamber for starting crude oil engines and containing a combustible element adapted by its combustion to provide heat of sufficient intensity and duration to start the normal ignition process and a phosphorus compound ignitable by the heat of air compression in said combustion chamber at a temperature below the ignition point of the oil.

2. A cartridge adapted to be inserted in the combustion chamber for starting crude oil engines having a tinder or carrier of combustible material adapted to burn with sufficient intensity and duration to start the normal ignition process and a pellet, of a phosphorous compound ignitable by the heat of air compression in said combustion chamber at a temperature below the ignition point of oil, applied to said tinder or carrier by means of an adhesive.

3. A cartridge for starting crude oil engines consisting of an insert element of combustible material adapted to burn with sufficient intensity and duration to start the normal ignition process and wholly or partially impregnated with a solution of a phosphorus compound ignitable by the heat of air compression at a temperature below the ignition point of the oil.

4. A cartridge as set out in claim 1 in which the phosphorus compound consists of phosphorus sesquisulphide.

5. A cartridge as set out in claim 2 in which the phosphorus compound consists of phosphorus sesquisulphide.

6. A cartridge as set out in claim 3 in which the phosphorus compound consists of phosphorus sesquisulphide.

7. A cartridge as set out in claim 1 in which the phosphorus compound is enclosed by removable frangible jacket.

8. A cartridge as set out in claim 2 in which

the phosphorus compound is enclosed by removable frangible jacket.

9. A cartridge as set out in claim 3 in which the phosphorus compound is enclosed by removable paper jacket.

10. A cartridge as set out in claim 3 in which the combustible material of said element is impregnated with saltpetre.

In testimony whereof I have hereunto
10 affixed my signature.

ARTUR MÖHRLE.
